W. T. DONNELLY.
METHOD OF RENDERING SHIPS UNSINKABLE.
APPLICATION FILED AUG. 28, 1914.

Patented Apr. 17, 1917.

UNITED STATES PATENT OFFICE.

WILLIAM T. DONNELLY, OF BROOKLYN, NEW YORK

METHOD OF RENDERING SHIPS UNSINKABLE.

1,223,154.

Specification of Letters Patent. Patented Apr. 17, 1917.

Application filed August 28, 1914. Serial No. 359,014.

To all whom it may concern:

Be it known that I, WILLIAM T. DONNELLY, a citizen of the United States, and a resident of Brooklyn, in the county of 5 Kings and State of New York, have invented certain new and useful Improvements in Methods of Rendering Ships Unsinkable, of which the following is a specification.

The invention relates to a method for insuring the safety of a ship and its cargo by rendering the same practically unsinkable should the vessel become water logged; or, in case of breaking up of the hull, to insure that the whole, or at least a portion, 15 of the cargo would float and could be reclaimed without damage.

To this end, the invention consists in disposing in the vessel suitable water-tight cells whose combined floating power or 20 buoyancy is greater than the total effective weight of the ship and cargo; or, in employing a portion or the whole of such cells as containers for the cargo, the individual cells being loaded to such an extent only 25 that they will be able to float in the water and to afford the required buoyancy to retain the ship afloat.

In the accompanying drawings which illustrate the invention, Figure 1 is a side 30 elevation of a freight carrying vessel provided with a shelter deck, a main deck, a second deck and a third deck. Figs. 2 to 6 are diagrammatic views, substantially a cross-section of the vessel, illustrating the 35 storage capacity and disposition of the cargo.

The legends above the various Figs. 3 to 6 set forth the character of the cargo and the ratio of the protected cargo to that 40 which might be carried with the space available for the particular ship. The legends to the left of the center line, indicate the usual loading for the respective spaces between the various decks, while the legends 45 to the right of the center line illustrate, with the particular character of the cargo employed, the disposition of the containers and the volume to be occupied by the same to render the ship non-sinkable.

50 Similar characters of reference designate corresponding parts throughout the several views.

Referring to the drawings, 10 designates the hull of a freighter which is divided into 55 a main deck 11, a second deck 12 and a third deck 13. A shelter deck 14, moreover, may

be provided; and the vessel is designed to carry 10,000 tons dead weight, coal for 12 days, fresh water and stores, the storage capacities for the various decks being indicated in Fig. 2.

If the freighter be loaded with material such as grain, for example wheat, (Fig. 3) the entire loading space may not be employed to receive the grain, but a portion 15 of the space between the second and third decks is filled with empty water-tight cells (indicated but not shown in detail) which may be of suitable shape to fit closely together and preferably be about the size 70 of an ordinary barrel. Moreover, a considerable portion 16 of the space between the main and second decks is to be similarly occupied by such cells. The remaining space 17 between the second and third decks and 75 the entire space 18 between the third deck and the ship's bottom is loaded with the grain, but which is contained in similar cells. Should the vessel break apart, the containers would, therefore, still float about 80 with their cargo which could be reclaimed, it being understood that the loading of the individual containers is such as to retain the latter afloat and to provide the required 85 buoyancy for the vessel. The load percentage is, however, somewhat reduced, being but approximately 90; but the added security afforded thereby, not only to the vessel and its crew but also to the cargo itself, 90 more than compensates for the reduced carrying capacity.

In Fig. 4, the disposition in the case of a load of coal is illustrated, the space between the third deck and bottom as well as a small portion 20 between the second and third decks being filled with the loose coal. The remaining space 21 between the second and third decks and the entire space 22 between the main deck and second deck is filled with cells, but in which no cargo is 100 included. The load percentage is still further reduced in this case and is approximately 78.

Referring to Fig. 5, a loading of ore is illustrated, and a considerably greater portion of the space is required to be occupied by the air tight containers. The load percentage, however, is substantially that in the case of coal.

Fig. 6 illustrates the disposition of a 110 mixed cargo and for which the load percentage is approximately 82. The cargo is

so mixed so that each kind of merchandise will occupy substantially the same amount of room.

The decrease of cargo carried in thus rendering the ship unsinkable varies from 10 to 20 per cent.; and the amount of cargo put into a container is governed by its specific gravity and is in such quantity only that the container itself is non-sinkable. In 10 case of breaking up of a ship, a container, therefore, would not only serve to preserve its contents, but, particularly in the case of the empty cells, would serve as a support or life-raft for the crew. It is understood, 15 of course, with respect to the use of the cells as hereinbefore set forth, that the construction of the various decks is such that they will be capable of withstanding the upward thrust due to the said cells, should the vessel become waterlogged.

I claim:—

1. The method of loading ships, which

consists in confining between decks water tight containers and loading a container with cargo to such an extent only that it 25 will float in water and will afford its portion of the buoyancy required to maintain the ship afloat when water logged.

2. The method of loading ships, which consists in confining between decks water 30 tight containers and distributing the entire cargo among the individual containers, each of which, however, is loaded to such an extent only that it will float in water and will afford its portion of the buoyancy required 35 to maintain the vessel afloat when water logged.

Signed at New York, in the county of New York, and State of New York, this 25th day of August A. D. 1914.

WILLIAM T. DONNELLY.
